By his Attorney
Henry C. Heinrich

UNITED STATES PATENT OFFICE

JOHN KLEIN, OF BROOKLYN, NEW YORK

TOBACCO PIPE

Application filed April 6, 1931. Serial No. 527,924.

This invention relates to improvements in smoking pipes, and it is the principal object of my invention to provide a readily removable cover for the pipe bowl, so that the pipe 5 may be used if so desired without the cover or the cover may be placed thereon and securely held in place on the bowl, if the pipe with the burning tobacco is to be placed into a pocket or the like when the user is entering a 10 place where smoking is prohibited, thus saving a considerable quantity of tobacco which is wasted in using uncovered pipes.

Another object of my invention is the provision of a cover for the bowls of tobacco 15 pipes which will be securely held in its bowl closing position, and which cannot accidentally come off the bowl if for instance the pipe is placed on a table, and thus prevent soiling of table covers or the like.

Still another object of my invention is the provision of a smoking pipe the upper margin of the bowl of which is equipped with one or more locking pins or screws adapted to firmly engage in suitable recesses of the 25 cover, said pins or screws serving as a protecting means for the bowl when the tobacco ashes are to be removed therefrom by the usual rapid striking of the bowl's margin against an object frequently being the cause 30 of breaking and otherwise damaging the bowl.

A further object of my invention is the provision of a tobacco pipe having a cover for its bowl pivoted about a pin entering a vertical bore in the bowl while a diagonally oppositely disposed pin on the upper margin of the bowl engages a groove on the under- 35 side of the cover.

A still further object of my invention is the provision of a tobacco pipe having a removable cover provided with a recess having bevelled walls adapted to be engaged by an angularly disposed finger pointing in a desired direction.

Other objects of my invention are the provision of a tobacco pipe the stem and mouth-piece of which have engaging tubes formed therewith, one for the reception of a saliva absorbing material while a chamber formed in the stem surrounding said tubes is adapted

to contain a removable element saturated with a deodorizing agent to prevent the saturation of the stem with tobacco odor, so that the pipe will at all times taste and smell sweet, as a ready renewal of this agent is 55 readily effected.

These and other objects and advantages of my invention will become more fully known as the description thereof proceeds, and will then be more specifically defined in the appended claims.

In the accompanying drawing forming a material part of this disclosure:

Fig. 1 is a top plan view of a pipe constructed according to my invention. 65

Fig. 2 is a side elevation, parts of the bowl being broken away.

Fig. 3 is a fragmentary perspective view of a pipe and bowl with the cover thereon.

Fig. 4 is a fragmentary top plan view of 70 a pipe and modified form of cover.

Fig. 5 is a sectional detail view of a bowl cover.

Fig. 6 is a sectional side elevation of a pipe showing the interior construction. 75

Fig. 7 is a cross-section on line 8—8 of Figure 6.

Fig. 8 is a detail view of a deodorizer element.

As illustrated, a pipe having a bowl 10, 80 stem 11 and mouth-piece or bit 12, has formed in the wall of the bowl 10 a vertical bore 13 adapted to receive a pin 14 formed with the cover 15 for the bowl or secured thereto in any suitable manner, as at 16. At a point diagonally opposite to the pin 14, the cover 15 has a recess 17 formed in its margin adapted to engage a pin or screw 18 in the wall of the bowl. Another recess 19 having bevelled 85 walls is formed in cover 15 near the pivot point of the same and is adapted to be engaged by a finger 20 projecting from the upper margin of the bowl and pointing in a suitable direction.

In the modified form of my device illustrated in Figures 4 and 5, the cover 15 has a groove 21 formed in its lower face having bevelled walls for engagement by a pin 22, snapping into said groove upon the closing 90 of the cover. 95

In Figures 6, 7, and 8, I have shown the interior arrangement of my pipe stem according to which a metal tube 23 arranged in the longitudinal bore of the stem is engaged by a similar tube 24 somewhat wider in diameter than the tube 23 and made integrally with the bit or mouth-piece 12. Any saliva absorbing means 25 is arranged in tube 24.

A chamber 26 is formed about tubes 23 and 24 and their point of union, for the reception of a body 27, for instance a wire covered with absorbent material impregnated with a deodorizing agent protecting the wood of the pipe against becoming saturated with the odor of nicotine.

The operation and use of my device will be readily understood from the above description and by simultaneous inspection of the drawing, and it will be clear that I have invented a tobacco pipe having a readily removable bowl cover which, however, will be effectively protected against accidental displacement and securely hold the tobacco in place within the bowl of the pipe even if burning so that the user will not have to waste perfectly good tobacco when entering a place where smoking is prohibited as for instance a street car or subway. The introduction of a saliva absorbing material and the placing of an exchangeable deodorizing member in the chamber 26 will prevent the wood of the pipe from becoming saturated with tobacco odor, thus presenting a cool and sweet smoke.

The cover locking pins will allow a striking of the pipe bowl, against objects in order to remove the ashes therefrom without damage to the bowl, while the cover will allow a laying away of the pipe without danger of spilling the tobacco on a table, cover, or other support.

It will be understood that I have shown and described the preferred forms of my invention as a few examples only of the many possible ways to practically construct my pipe and cover therefor, and that I may make such changes in its general construction and its minor details as come within the scope of the appended claims without departure from the spirit of my invention, and the principles involved.

Having thus described my invention what I claim as new and desire to secure by Letters Patent is:

1. A smoking pipe including its bowl having a vertical recess formed in its wall, a cover having a plurality of recesses formed in its margin, a pivot stem on said cover entering the vertical recess to removably and turnably hold said cover to the bowl, a pin in the upper margin of the bowl diametrically opposite to the pivot stem to engage one of the recesses in said cover, a finger on said bowl near the pivot stem engaging the other of said recesses for securely holding the cover in

its bowl closing position preventing accidental displacement.

2. In a cover for the bowls of smoking pipes having a groove formed in its underside, a pivot pin entering the bowl and secured to said cover for holding the same removably and turnably to said bowl, and a pin on said bowl adapted to engage the groove in said cover for locking the same in its bowl covering position.

Signed at New York, in the county of New York and State of New York, this 2nd day of April A. D. 1931.

JOHN KLEIN.
